DESIGN FOR A TEXTILE FABRIC OR SIMILAR ARTICLE

Emanuel Mentz, New York, N. Y.

Application March 21, 1940, Serial No. 91,126

Term of patent 3½ years

To all whom it may concern:

Be it known that I, Emanuel Mentz, a citizen of the United States of America, residing in New York city, in the Borough of Manhattan, county and State of New York, have invented a new, original, and ornamental Design for a Textile Fabric or Similar Article, of which the following is a specification, reference being had to the accompanying drawing, forming part thereof, wherein the figure is a plan view of a piece of textile fabric showing my new design.

I claim:

The ornamental design for a textile fabric or similar article, substantially as shown.

EMANUEL MENTZ.
